UNITED STATES PATENT OFFICE.

VICTOR H. JENNINGS, OF WORCESTER, MASSACHUSETTS, ASSIGNOR TO UNIVERSAL PATENTS COMPANY, OF WOONSOCKET, RHODE ISLAND, A CORPORATION OF RHODE ISLAND.

MACHINE-GUN BELT AND THE LIKE.

1,346,208.

Specification of Letters Patent. Patented July 13, 1920.

Original application filed May 1, 1917, Serial No. 165,666. Divided and this application filed January 2, 1920. Serial No. 348,946.

To all whom it may concern:

Be it known that I, VICTOR H. JENNINGS, a citizen of the United States, residing at Worcester, in the county of Worcester, State 5 of Massachusetts, have invented a certain new and useful Improvement in Machine-Gun Belts and the like, of which the following is a specification, reference being had therein to the accompanying drawings.

10 The invention is a division of that originally forming the subject-matter of my application for U. S. Letters Patent for improvements in machine-gun belts and the like, filed May 1, 1917, Serial No. 165,666. 15 It is an improvement in machine-gun belts and other carriers of the same general character and construction as those used as machine-gun belts. It provides in novel and improved manner for the combination with 20 such belts or carriers of means for stiffening or reinforcing them transversely; it provides for the employment of stiffening means of simpler and less expensive character than heretofore employed; it lessens 25 the manufacturing cost.

The invention is applicable in the case of belts or carriers of the type composed of a web woven in separated plies at intervals so as to form transversely extending loops or 30 pockets for the reception of cartridges or other articles, and having such plies joined together and united in the weaving between one loop or pocket and the next so as to form the divisions between the successive pockets.

35 In practice heretofore the stiffening means employed has comprised strips of metal, called clips, extending crosswise of a belt or carrier in pairs between adjacent loops or pockets, one metal strip or clip of a pair at 40 one surface of the belt or carrier and the other thereof at the opposite surface of the belt or carrier, with the two metal strips or clips of a pair bound together by rivets, usually eyelets. At regular intervals a pair 45 of the metal strips or clips projects beyond one edge of the belt or carrier to serve as "guides" in guiding the charged belt or carrier through a machine-gun. The said metal strips or clips stiffen or reinforce the belt or carrier transversely so that it will not 50 cripple or yield transversely when the cartridges are being pushed home within the loops into which they are inserted in loading the belt or carrier. The cost of the metal strips or

clips and the eyelets, and the expense incident to applying the said strips or clips and securing them in place, increase considerably the cost of belts or carriers made as heretofore.

55 The invention consists, essentially, in a belt or carrier having transverse loops for the reception of cartridges or other articles, and also formed between the successive loops with transversely extending pockets or tubes containing reinforcing or stiffener strips, 60 with the said pockets or tubes closed at both ends thereof, a slit or opening located at an intermediate point in the length of a pocket or tube being provided for the insertion of 65 a reinforcing or stiffener strip.

70 Illustrative embodiments of the invention are shown in the drawings, in which latter,—

75 Figure 1 is a perspective view showing a portion of the length of a machine-gun belt or carrier containing one of the said illustrative embodiments of the invention, with cartridges occupying the loops thereof. A small portion of the woven fabric is represented as broken away to show a reinforcing or stiffener strip.

80 Fig. 2 is a longitudinal section of the portion of belt or carrier shown in Fig. 1, on a relatively enlarged scale, without any cartridges.

85 Fig. 3 is a cross-section on line 3—3, Fig. 1, also on a relatively enlarged scale.

Fig. 4 is a cross-sectional view showing another of the illustrative embodiments.

90 The machine-gun belt that is illustrated in Figs. 1, 2 and 3 of the drawings comprises an integral web woven at intervals in separate plies, 1, 1, so as to form between such plies the transversely extending loops 1^a for the reception of cartridges 2, 2. In carrying the invention into effect, the divisions 95 between the said loops, formed by joining the said plies together and uniting them in the weaving, are woven so as to provide transversely extending pockets or tubes 3 for the reception of the reinforcing or stiffener strips 4, 4^a. The strips 4^a are longer than the strips 4 and project at one edge 100 of the belt or carrier to serve as guides in the well-known manner in guiding the charged belt or carrier through a machine- 105 gun. The invention is shown embodied in connection with the pockets or tubes receiving the short strips 4 which do not project

at an edge of the belt or carrier. The pockets occupied by the guide-strips 4^a are open at one edge of the belt or carrier to permit the end-portions of the said strips 5 4^a to project beyond such edge, but the pockets or tubes 3 for the reception of the shorter strips, 4, are closed at both edges of the belt or carrier as illustrated in Fig. 3, to prevent displacement of the reinforcing 10 or stiffener strips 4 lengthwise in either direction. Preferably the pockets or tubes occupied by the guide-strips 4^a are woven closed along the edge of the belt or carrier opposite that at which they project.

15 A belt or carrier such as that shown in Figs. 1, 2 and 3 is produced by weaving the plies 1, 1, separate from each other to form a cartridge-receiving loop, then binding the two plies together in the weaving at 5 crosswise of the web to close the said loop at one side thereof, then weaving separate plies 6, 6, to form a stiffener receptacle or tube, with such plies united in the weaving along both edges of the web as clearly indicated 20 in Figs. 1 and 3, with an intermediately-located slit 3^b in one ply for the insertion of a strip 4. The plies are then bound together in the weaving at 7 crosswise of the web to close the said receptacle or tube, then separate plies 1, 1, are woven to form a second cartridge-receiving loop, and so on. This mode of weaving produces a belt or carrier woven at intervals in two plies which are separated to form open-ended pockets or 35 loops for the insertion of cartridges, and between the cartridge-receiving loops woven with divisions having receptacles or tubes, for the reception of stiffening or reinforcing strips, such receptacles or tubes closed 40 at both ends and provided with an intermediate opening for the insertion of the stiffening or reinforcing strips.

The stiffening or reinforcing strips may be of any suitable and approved material, although in practice strips of walohn are

preferred. Walohn, so-called, is steel coated with rubber. The strips ordinarily will be proportioned to fit snugly and tightly in their respective receptacles or tubes in the web of a belt or carrier. The frictional 50 hold of the walls of the receptacles or tubes upon the strips may be depended upon to hold the guide-strips 4^a from displacement outward through the openings located at one edge of the belt or carrier in the case of 55 the receptacles or tubes occupied by the guide-strips, although fastenings or securing means may be employed if deemed or found desirable.

In Fig. 4 the opening for the insertion of 60 the stiffening or reinforcing strip 4^b extends across a considerable portion of the width of the belt or carrier, and the intermediate portion of the length of the strip 4^b is fastened down by means of an eyelet 65 3^d. Some other convenient form of fastening might be adopted instead of the eyelet 3^d.

The belt or carrier may be beaded, as usual, along the edge thereof at which the 70 guides project, if desired. The beading is omitted from the drawings for convenience in illustration.

I claim as my invention, —

A belt or carrier having transverse loops 75 for the reception of cartridges or other articles, having between the successive loops transversely extending pockets or tubes containing reinforcing or stiffener strips and closed at both ends thereof, and having 80 slits or openings intermediate said ends to provide for the insertion of the reinforcing or stiffener strips.

In testimony whereof I affix my signature in presence of two witnesses.

VICTOR H. JENNINGS.

Witnesses:

ALICE M. TISDALE,
A. LORETTA MATTIMORE.

It is hereby certified that Letters Patent No. 1,346,208, granted July 13, 1920, upon the application of Victor H. Jennings, of Worcester, Massachusetts, for an improvement in "Machine-Gun Belts and the like," were erroneously issued to "Universal Patents Company, of Woonsocket, Rhode Island," whereas said Letters Patent should have been issued to *Frank R. Batchelder, of Worcester, Massachusetts*, said Batchelder being assignee, *by mesne assignments*, of the entire interest in said invention, as shown by the records of assignments in this office; and that the said Letters Patent should be read with this correction therein that the same may conform to the record of the case in the Patent Office.

Signed and sealed this 22d day of February, A. D., 1921.

[SEAL.]

L. B. MANN,

Acting Commissioner of Patents.
